UNITED STATES PATENT OFFICE.

JOHN J. PUNKE, OF DETROIT, MICHIGAN, ASSIGNOR TO HUPP MOTOR CAR CORPORATION, OF DETROIT, MICHIGAN, A CORPORATION OF MICHIGAN.

DESIGN FOR A DOOR-CONTROL GARNISH PANEL.

Application filed May 28, 1928. Serial No. 26,894. Term of patent 7 years.

To all whom it may concern:

Be it known that I, JOHN J. PUNKE, a citizen of the United States of America, residing at Detroit, in the county of Wayne and State of Michigan, have invented a certain new, original, and ornamental Design for Door-Control Garnish Panel, of which the following is a specification, reference being had therein to the accompanying drawing, in which—

Figure 1 is a front elevation of my door control garnish panel, and Figures 2, 3 and 4 respectively, are enlarged sectional views taken on the lines 2—2, 3—3 and 4—4, respectively of Figure 1.

I claim:

The ornamental design for a door control garnish panel, substantially as shown.

JOHN J. PUNKE.
